DESIGN FOR A TRAY

Lurelle Guild, Noroton, Conn., assignor to Kensington, Incorporated, New Kensington,
Pa., a corporation of Pennsylvania

Application January 14, 1936, Serial No. 60,578

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Tray. The application of which the following is the specification is a continuation in part of application Serial No. D—53,558, filed October 11, 1934, reference being had to the accompanying drawing forming a part hereof.

Fig. 1 is a top view and Fig. 2 is a side view having a fragmentary section of a tray embodying my new design.

I claim:

The ornamental design for a tray as shown.

LURELLE GUILD.
